HAND GRIP FOR BICYCLE OR MOTOR BIKE HANDLE BARS

Eugene M. Jamison, Columbus, Ohio
(27640 Gateway Drive E., Farmington, Mich. 48024)

Filed Mar. 8, 1973, Ser. No. 339,416

Term of patent 14 years

Int. Cl. D12—II

U.S. Cl. D8—138

FIG. 1

FIG. 2

FIG. 3

FIG. 1 is a front perspective view of a handle grip for bicycle or motor bike handle bars showing my new design;

FIG. 2 is a side elevational view thereof;

FIG. 3 is a right end elevational view.

The side of the handle grip not shown in FIG. 1 is the same as and symmetrical with the side shown.

I claim:

The ornamental design for a hand grip for bicycle or motor bike handle bars, substantially as shown and described.
